UNITED STATES PATENT OFFICE

169,941

CALCULATOR

Kurt P. Jaeger, Miami, Fla.

Application November 5, 1952, Serial No. 22,134

Term of patent 14 years

(Cl. D64—11)

To all whom it may concern:

Be it known that I, Kurt P. Jaeger, a citizen of the United States, residing at Miami, county of Dade and State of Florida, have invented a new, original, and ornamental Design for a Calculator, of which the following is a specification, reference being had to the accompanying drawings, forming a part thereof.

Figure 1 is a front elevation of a calculator,
Figure 2 is an edge view thereof, and
Figure 3 is a rear elevation thereof.

I claim:

The ornamental design for a calculator, as shown.

KURT P. JAEGER.
